UNITED STATES PATENT OFFICE.

LEVI STEVENS, OF BOSTON, MASSACHUSETTS.

HYDROCARBON-BURNER.

SPECIFICATION forming part of Letters Patent No. 394,517, dated December 11, 1888.

Application filed October 29, 1887. Serial No. 253,741. (No model.)

To all whom it may concern:

Be it known that I, LEVI STEVENS, of Boston, in the county of Suffolk and State of Massachusetts, have invented certain new and useful Improvements in Hydrocarbon-Burners; and I do hereby declare that the following is a full and exact description thereof, reference being had to the accompanying drawings, and to the letters of reference marked thereon, making a part of this specification, in which—

Figure 1 is a top view of my improved hydrocarbon-burner; Fig. 2, a vertical central section of the same; and Fig. 3 is an elevation of a vertical-flue boiler having its lower portion broken away to illustrate the use of the burner in connection therewith.

This invention relates to a hydrocarbon-burner in which the oil is vaporized, and the vapors, mixed with superheated steam and air at a temperature of about 600° Fahrenheit, are delivered through the nozzle of a burner to be thereat ignited.

The object of my invention is to provide a more compact and efficient device for burning the vapor of crude petroleum commingled with superheated steam than those heretofore employed for the purpose, and wherein all the constituents of the oil shall be vaporized and consumed, so as to obviate thereby not only the difficulties and disadvantages which have heretofore attended the burning of heavy hydrocarbon oils by reason of the deposit of the asphalt and other heavy products of the oil in the chambers, tubes, or nozzles of the burners, but also to obtain a complete combustion thereof, and consequently a much higher temperature or percentage of heat from the oil.

It consists in a novel construction and arrangement of the several parts of the burner, as hereinafter particularly described and claimed, whereby the steam admitted to the device is superheated in a retort exposed directly to the jets of flame issuing from the nozzles of the burner, and is thereafter carried through a conduit leading through an oil-receptacle into a chamber beneath said receptacle, so as to produce a vaporization of the oil, and is finally discharged through tubes passing through the oil-receptacle into nozzles communicating therewith, whereby

the vapor of the oil, commingled with a supply of air admitted under the nozzles and with the superheated steam to form an inflammable gas, is delivered through the nozzles for combustion.

In the accompanying drawings, A represents a circular plate constituting the base of my improved burner; B, a circular cap-plate or casing of preferably the same diameter as the base, and which is provided at its lower edge with a radial flange, preferably made to project inward, whereby it may be bolted to the base to form a steam-tight joint therewith. When thus secured, the casing incloses a circular steam-chamber, C, above the base A. The upper surface of the casing B is conical or inwardly inclined from its circumference to its center, as shown in Fig. 1, and is formed with a comparatively large central opening, D, which is internally threaded. A second circular cap-plate or casing, E, is fitted with a tight joint upon the rim of the casing B, so as to leave an open space or oil-chamber, F, between them. The top of this casing E is made conical or inwardly inclined toward the center at an angle corresponding with that of the top of the casing B, so that the two opposing surfaces shall be parallel, and it is likewise centrally pierced with an opening, G, slightly larger in diameter than the threaded opening D in the casing B.

A cylindrical vessel or retort, H, preferably enlarged or pear-shaped at its upper closed end and of a diameter at its lower open end corresponding with that of the aperture D in the lower casing-plate B, is inserted through the aperture G in the casing-plate E and screwed at its lower open end into the threaded aperture D. This central retort, H, is provided with an annular flange, I, encircling it in such manner as that when its lower end is screwed to the casing B said flange shall bear upon the margin of the casing-plate E about its central opening, and a washer, m, of asbestos or other fire-proof packing, is inserted under the flange to make the joint tight and steam-proof. The retort H thus forms in effect an upward central extension of the lower steam-chamber, C. A series of small openings, k k, are pierced concentrically in the top of the casing B near to its outer edge. A similar series of larger openings, l l, are

pierced in the top of the casing E in such manner as that the corresponding openings k and l in the two plates shall have a common axis, (see dotted lines in Fig. 2,) said axis being so 5 inclined by reason of the inclination of the plates as to intersect the central retort, H, somewhat below the top thereof. A small nipple, N, having a slight cylindrical bore is screwed into each of the apertures k in the 10 plate B, and a larger nozzle, P, preferably flaring more or less at either end, is screwed into each of the apertures l in the plate E.

Minute apertures R R are pierced in the lower end of the vessel H to establish vents 15 from the interior thereof into the chamber F. A cylindrical casing, S, of sheet metal is fitted upon the rim of the upper plate, E, to project therefrom to a level above the nozzles P P. A series of air-holes, T T T, are preferably 20 pierced in the wall of the casing E, close under the top thereof, whereby a supply of air is admitted directly to the nozzles P P.

The oil-supply pipe V, for feeding the burner, is connected directly with the chamber 25 F, and the steam-supply pipe W is passed through the base of the device with a threaded joint, so as to project up into the central retort, H, nearly to the top thereof, as shown in Fig. 2.

30 It is evident that the device may be constructed in a rectangular or other form instead of being made circular, as described, and that the upper surfaces of the two chambers C F may be flat instead of inwardly 35 inclined, it being, however, desirable that the nipples and nozzles shall incline toward the central retort, so as to cause the flame issuing from the nozzles to impinge thereon or to come into close proximity 40 thereto; also, that the manner of uniting the several parts and of forming the chambers may be varied, the chambers C and F admitting of being formed in one casting. It is preferable, however, to make the several parts 45 separable, as described, to facilitate cleaning or renewing the same, and the circular form has also been found the most practical for general use.

To maintain automatically the relative proportions of the steam and oil admitted to the 50 burner which may be desirable under any given conditions, I combine with the steam-supply pipe W a chamber, 10, divided into two compartments by a flexible steam-proof 55 diaphragm, 11, of steel, rubber, or other suitable material. One of the compartments in the chamber communicates freely with the steam-pipe and the other is open to the air. The diaphragm 11 is connected by means of a 60 rod, 13, with the stem or lever of a valve, 12, of any suitable description, controlling the oil-supply pipe V. Said rod 13 is attached to the center of the diaphragm, and, passing through the open compartment of the diaphragm- 65 chamber, is connected with the valve stem or lever in such manner as that when the diaphragm is forced outwardly by the pressure

of steam against its inner side it will operate to open the valve, and will close it when moved inwardly. The diaphragm-rod 13 is 70 slotted or provided with a lateral pin or an offset, as at 17, to furnish a bearing for a lever, 14, pivoted at one end to a suitable support, 15, and fitted at its free end beyond the diaphragm-rod with a sliding weight, 16, 75 whereby a determinate pressure may be applied to the diaphragm to counterbalance the steam-pressure and thereby determine the point at which the pressure shall operate to open the oil-valve 12. 80

In the operation of this regulating device, when the steam-pressure, and, consequently, the volume of steam delivered into the retort H, increases the pressure onto the diaphragm 11, it will open the oil-valve 12 more widely, and 85 thus permit an increased flow of oil to the burner proportionate to the increase in the steam-supply, and, vice versa, as the steam-pressure diminishes and permits inward movement of the diaphragm, the oil-valve is correspondingly closed and the oil-supply diminished, the relative proportion of steam and oil being primarily adjusted by an adjustment of the oil-valve with reference to the position of the diaphragm and changed as required by 95 means of the sliding weight 10, which governs the pressure at which the diaphragm is permitted to move to influence the valve.

In the use of the burner it is preferred to 100 heat it at the start by pouring a small quantity of oil into the central depression encircling the vessel H on the top of the casing E and firing the same. Steam being now admitted from the pipe W and oil from the pipe V, the steam will be superheated in the retort H, 105 and, passing down thence to the steam-chamber C, will issue therefrom in fine jets through the nipples N N and be forcibly discharged into the nozzles P P, thereby creating a partial vacuum in the oil-chamber F. This chamber F will at the same time become heated to 110 a high temperature by radiation from the casing B of the steam-chamber C and from the covering-plate E. The oil flowing into the hot chamber F will be vaporized therein, 115 and the vapor will be drawn up and carried by the jets of steam into the nozzles P P, and, commingling therein with the steam and with a supply of air simultaneously drawn in through the apertures T T, will form a highly-combustible compound, which, being ignited at the nozzles, will produce an intense flame. 120

The jets of flame issuing from the several nozzles P P are made to converge upon the central superheated retort, and are deflected 125 thence in a crown of fire above the casing, creating an intense heat, which may, however, be regulated at will by regulating the supply of oil and steam.

The deposit of tar or of any other of the 130 heavier products of the oil which would under ordinary conditions occur in the chamber F, and which would operate to clog and choke the same and in a short time render

the burner inoperative, is prevented by the admission into said chamber of one or more jets of superheated steam directly from the retort through the apertures R R.

5 I do not claim as new a device for superheating steam within a retort heated by the flame of a hydrocarbon-burner to which the steam from the retort is admitted, and I am aware that hydrocarbon-burners have here-
10 tofore been constructed in which an oil-cham-
ber is formed over a steam-chamber and the steam is delivered into nozzles in the top of the oil-chamber through tubes extending through the same from the steam-chamber.

15 My invention is novel in that it involves a combination, with superimposed oil and steam chambers, of a central retort carried up from the steam-chamber through the oil-chamber and outwardly far enough to be acted upon
20 by the flames from the burners fitted in the top of the latter, and of a steam-supply pipe carried up within said retort nearly to the top thereof, thereby producing a circulation of steam from the top of the retort downward
25 into the steam-chamber underlying the oil-chamber, whereby the latter is heated to a point at which the oil admitted thereto will be vaporized in readiness for admixture with the steam in the nozzles.

30 I claim as my invention—

1. The combination, in a hydrocarbon-
burner, of a steam-chamber, a superimposed
oil-chamber, a central superheating-retort ex-
tending above the oil-chamber and communi-

cating freely with the steam-chamber, flame- 35
nozzles fitted in the outer casing of the oil-
chamber, each at an angle adapted to carry
the flame therefrom into close proximity to
said retort, discharge-nipples projecting from
40 the steam-chamber into the flame-nozzles, and
a steam-supply pipe carried within the super-
heating-retort nearly to the top thereof, all
substantially in the manner and for the pur-
pose herein set forth.

2. The combination, in a hydrocarbon- 45
burner, of a steam-chamber, a superimposed
oil-chamber, a central superheating-retort ex-
tending above the oil-chamber and communi-
cating freely with the steam-chamber, and
45 through one or more small apertures with the
oil-chamber, flame-nozzles fitted in the outer
casing of the oil-chamber, each at an angle
adapted to carry the flame therefrom into close
50 proximity to said retort, discharge-nipples
projecting from the steam-chamber into the
flame-nozzles, a steam-supply pipe carried
within the superheating-retort nearly to the
55 top thereof, and ports for supplying air to
the flame - nozzles, all substantially in the
manner and for the purpose herein set forth. 60

In testimony whereof I have signed my name
to this specification in the presence of two sub-
scribing witnesses.

LEVI STEVENS.
